UNITED STATES PATENT OFFICE

142,672

DESIGN FOR A SET OF GAME PIECES

Henry Schirokauer, New York, N. Y.

Application July 5, 1945, Serial No. 120,528

Term of patent 14 years

(Cl. D34—5)

To all whom it may concern:

Be it known that I, Henry Schirokauer, a citizen of Germany, residing at New York city, State of New York, have invented a new, original, and ornamental Design for a Set of Game Pieces, of which the following is a specification, reference being had to the accompanying drawing, forming part thereof.

In the accompanying drawing:

Figs. 1, 2, 3, 4, 5 and 6 are side elevational views of the various game pieces of the set constituting my new design;

Figs. 1a, 2a, 3a, 4a, 5a and 6a are plan views, respectively, of the pieces shown in Figs. 1, 2, 3, 4, 5 and 6.

I claim:

The ornamental design for a set of game pieces, substantially as shown.

HENRY SCHIROKAUER.
